NURSING BOTTLE SUPPORT

Lillian L. Menk, Shaker Heights, Ohio

Application September 19, 1935, Serial No. 41,265

3 Claims. (Cl. 248—105)

This invention relates to a nursing bottle support.

One of the objects of my invention is to arrange a nursing bottle upon a support in such a manner that the bottle will be presented in a suitable position to a baby lying upon a pillow or other head rest. My improved support is of sufficient stability to hold a nursing bottle in position alongside the child's head and to maintain it there so that if the child turns its head away and again turns back seeking the nipple of the bottle it is still maintained in much the same position as it would be by a person holding it.

My invention also provides a nursing bottle support which is also adapted to protect the bottle against breakage if it should fall while carried by the supporting member.

Another feature of my invention is the arrangement of the support to hold the bottle either in a substantially horizontal position or in a substantially vertical position.

Other advantages of my invention will appear from the accompanying specification and drawings and the essential features will be set forth in the claims.

In the drawing, Fig. 1 is a plan view of one form of my improved bottle support showing a bottle in place therein; Fig. 2 is a longitudinal section along the line 2—2 of Fig. 1; Fig. 3 is a transverse section along the line 3—3 of Fig. 2; Fig. 4 is a longitudinal section through a modified form of bottle support; while Fig. 5 is a transverse section along the line 5—5 of Fig. 4; and Fig. 6 is a transverse section of another modification.

In the form of the device shown in Figs. 1 to 3, I have provided a block 10 preferably of sponge rubber having a base 11 substantially flat and adapted to rest for instance upon a pillow alongside a baby's head. The upper face of the block opposite the base 11 is provided with a suitable deformation to receive and hold a nursing bottle 12 of well known type. In the form shown this deformation is substantially a groove extending part way across the upper face of the block and ending at a wall or shoulder 13 which extends upwardly along the base of the bottle in its reclining position. Preferably the floor or bottom surface 14 of the groove is inclined relative to the base 11 so as to hold the bottle 12 inclined downwardly toward its nipple 15 so that liquid will be properly presented to the nipple. In this form of the device portions 16 of the sponge rubber block extend upwardly alongside the

bottle and these portions in turn have lip portions 17 which overlie the bottle in its reclining position. With this form of device the bottle is easily placed in position in the deformation either by pushing the same downwardly between the lips 17 or by inserting it lengthwise in the groove portion of the block. It will be noted that the end surface 18 of the rubber block is formed substantially at right angles to the base 11 and if it is desired to set the bottle down in an upright position the surface 18 will support the bottle in an upright position without danger of the same being knocked over. If the bottle should fall it is protected by the sponge rubber block at all points except at the nipple end and this end is partly protected by the nipple and is in any case not so likely to be injured, as the bottle when in the support would generally fall with the face 18 downward. While I have shown a full size eight ounce bottle in full lines in the illustration it will be understood that bottles of less capacity and of similar cross section may be utilized in the same device, the position of a much smaller bottle being indicated by dot-dash lines in Figs. 1 and 2.

A modified form of device is shown in Figs. 4 and 5 as comprising a sponge rubber block 19 having a base 20 as before and a groove extending entirely across the upper face of the block, the floor of the groove at 21 being inclined relative to the base 20 in a manner analogous to that already described. Side portions 22 of the sponge rubber extend upwardly alongside the bottle in its reclining position and preferably extend slightly above the upper surface of the bottle so as to aid in gripping the same and to protect the bottle if it should fall. Preferably also a portion 23 of this block extends beyond the base of the longest bottle used therein so as to protect the base of the bottle against striking an object if the bottle should be dropped while supported on the block. As an aid in retaining the bottle in this form of device I may use a flexible band 24 which may if desired also be resilient, for instance the usual rubber band may be used.

In either form of the device the bottle after insertion in the holder or sponge rubber block may rest upon the base 11 or 20 on a pillow alongside the baby's head and will very firmly hold the bottle with the nipple in the proper position until the baby has finished with the same.

I find an additional advantage in making the bottle support of sponge rubber as the rubber

base may be cut up and used for sponge purposes when the support is no longer desired for the nursing bottle.

Sponge rubber forms a heat insulating layer about the bottle which aids in maintaining a more or less constant temperature of heated milk or other liquid fed to a child. Any of the forms shown will have this insulating effect but in Fig. 6 I have shown a view of a modified form with increased heat insulating effect. This modification is similar in all respects to that shown in Figs. 1 to 3 except that the sponge rubber completely surrounds the bottle, there being a continuous upper wall at 25 instead of the cut-away construction of Figs. 1 to 3.

A bottle support of sponge rubber is easily cleansed and sterilized when this becomes necessary because of milk or other food deposited on it. The entire article may be thrown in boiling water without injuring it.

I do not desire to limit my invention to sponge rubber but may use other materials having similar properties.

What I claim is:

25. 1. A nursing bottle support comprising an elongated block of sponge rubber having a flat base on one of its longer faces, there being a groove extending longitudinally part way across the face of said block opposite said base and 30 adapted to receive a nursing bottle, the portion of said block at the end of said groove being coextensive with the thickness of said bottle to

protect the bottom thereof, the portions of said block forming the side walls of said groove having lip portions adapted to overlie a bottle in said groove, and the base of said groove being inclined relative to the base of said block. 5

2. A nursing bottle support comprising an elongated unitary block of sponge rubber having a base surface on one of its longer faces adapted to maintain the support in position upon a head rest for a child, and said block having a pocket 10 therein adapted to completely surround a nursing bottle except for its nipple end, said pocket being arranged to hold said bottle slightly inclined toward its nipple end when said base surface engages said head rest. 15

3. A nursing bottle support comprising a unitary block of sponge rubber one face of which is adapted to serve as a base, there being a recess centrally of said block inclined downwardly toward one end thereof, said recess being 20 open at said one end, there being a portion of the block closing said recess at the other end, said recess being of a length and depth to encompass substantially entirely except for the nipple end the largest bottle intended for use 25 therein, and there being a slotted opening of less width than said recess from the top of said block to said recess extending longitudinally of said recess and adapted for introduction of a bottle 30 into said recess.
